CLAIM

The ornamental design for an arrow vane as shown and described.

DESCRIPTION

FIG. 1 is a front perspective view of the arrow vane; FIG. 2 is a top view thereof; FIG. 3 is a right side view thereof, the left side view being a mirror image thereof; FIG. 4 is a bottom view thereof; FIG. 5 is a front view thereof; and, FIG. 6 is a rear view thereof. FIGS. 1-6 show features of an arrow vane in broken lines. These features form no part of the claimed design.
